UNITED STATES PATENT OFFICE.

OLIVER S. BOWMAN, OF COLORADO SPRINGS, COLORADO.

FORMING MACHINE.

Application filed November 15, 1924. Serial No. 750,196.

To all whom it may concern:

Be it known that I, OLIVER S. BOWMAN, a citizen of the United States, and a resident of Colorado Springs, in the county of El Paso and State of Colorado, have invented a new and useful Forming Machine, of which the following is a specification.

My invention relates to forming machines and has for its object the provision of a machine of this class which will feed, punch, shear, form and deliver a sheet metal angle of the form described and claimed in my Patent No. 1,520,325, dated Dec. 23, 1924. Other objects will appear as the description progresses.

Although I have shown the preferred embodiment of my invention, I do not thereby confine myself to the precise construction shown but wish it understood that various changes in the details may be made within the scope of the claims.

The drawings are for illustrative purposes and are therefore not drawn to scale.

Figure 1 represents a plan view of the strip of sheet metal perforated and slotted but not formed; Fig. 2, an end elevation of the sheet metal angle; Fig. 3, a plan view of the angle showing the shape into which it is adapted to be bent to form a component of a polygonal mold; Fig. 4, a transverse section on the line 4—4 in Fig. 6, partly broken away; Fig. 5, a longitudinal section on the line 5—5 in Fig. 6; Fig. 6, a plan view, partly in section; Fig. 7, an end, a side, and an end elevation of the cylinder 36; Fig. 8, an end and a side elevation of the collar 37; Fig. 9, a side and an end elevation of the collar 38; Fig. 10, an end elevation showing the knives 39 disposed between collar 37 and cylinder 36; Fig. 11, an end elevation of the collar 38, showing the pins 40 disposed between collars 38 and cylinder 36; Fig. 12, elevations of the knife 39; Fig. 13, a detailed view of the ratchet mechanism, and Fig. 14, a detailed view of the off-bearing arms and tilting means therefor.

The machine comprises a frame 1 having guideways 2—3; a fixed die 4, having a longitudinal rib 5, bolted to frame 1; a shear blade 6 bolted on the back of said fixed die; a bending plate 7 bolted on the front of said fixed die; a shim 7^a disposed between said die and said bending plate; a vertically movable die 8, having a longitudinal groove 9 adapted to receive rib 5, transverse grooves 10, and downwardly ex-

tending slides 12, mounted in said guideways; roller 13 mounted on said slides; a shear blade S bolted on the back of die 8; a brake plate T bolted on the front of die 8; a shim 9 disposed between die 8 and plate T; a main shaft 14 journaled in frame 1; cams 15 mounted on shaft 14 and adapted to cooperate with rollers 13; a drive wheel W mounted on shaft 14; brackets 16 bolted to die 8; a supplementary shaft 17 journaled in brackets 16; off-bearing arms 17^a mounted on shaft 17 and normally resting in grooves 10 in die 8; a tilting arm 18 mounted on shaft 17; a slotted bar 19, having its slotted portion disposed around shaft 14 and its upper end connected to tilting arm 18; a segmental cam 20 mounted on shaft 14; a roller 21 mounted on bar 19 and adapted to cooperate with segmental cam 20; a pair of shafts 22—23 journaled in frame 1 and carrying sprockets 24; sprocket chains 25, having standards 26, mounted on said sprockets; a crank 55 mounted on shaft 22; an upper feed roller shaft 27, carrying a ratchet wheel 28, mounted in frame 1 at the rear of said dies; a lever 29 mounted on shaft 27 and carrying pawl 30 adapted to engage ratchet wheel 28; a crank 31 mounted on shaft 14; a link bar 32 connecting lever 29 and crank 31; a lower feed roller shaft 33, having a gear 34 mounted thereon, journaled in frame 1 directly below shaft 27; a gear 35 mounted on shaft 27 and meshed with gear 34; two slitting and perforating feed rollers mounted on shaft 27, each roller comprising a cylinder 36 having rectangular radial grooves *a* in one end and semicircular grooves *b* in the opposite end, a collar 37, having similar rectangular radial grooves *c*, disposed with grooves *c* adjacent to grooves *a*, a collar 38 having semicircular radial grooves *d*, disposed with grooves *d* adjacent to grooves *b*, knives 39, having two slitting segments, disposed in rectangular grooves *a* and *c*, and pins 40 disposed in semicircular grooves *b* and *d*, said cylinder and collars being clamped together by bolts 41 extending longitudinally through said collars and cylinder; two perforating feed rollers mounted on shaft 27, each roller comprising a pair of collars 44 and 45, having semicircular radial grooves, said collars being disposed with the radial grooves of one adjacent to the radial grooves of the other, and pins 46 disposed in said radial grooves and clamped therein by bolts ex-

tending through said collars; two feed rollers 42 mounted on shaft 33 adjacent to said slitting and perforating feed rollers and having peripheral grooves *f* adapted 5 to receive knives 39 and pins 40; two feed rollers 47 mounted on shaft 33 adjacent to said perforating feed rollers and having peripheral grooves *h* adapted to receive pins 46; two guide collars 56 mounted on 10 shaft 33; a shaft 49 journaled in the rear of frame 1 and carrying flanged guide rollers 50-51 and a supporting roller 52.

Power is applied to drive wheel *W* which rotates shaft 14 carrying crank 31. Each 15 revolution of crank 31 swings arm 29 in an arc of ninety degrees. At the end of the downward swing, pawl 30 engages ratchet wheel 28 and, by the upward swing, rotates shaft 27 one fourth of a revolution, which 20 feeds the required amount of sheet metal to make the angle 54. During the feeding, the knives 39 slit the metal and the pins 40 and 46 perforate it as shown at *g*, *k*, and *p* in Fig. 1. When arm 29 is at the highest 25 point, cams 15 coact with rollers 13 and lift die 8 and thereby cause shear blades *S* and *6* to cut off the strip of metal 53, the rib 5 and groove 9 to form the corrugation, and plate 7 to bend the angle over plate *T*, thereby 30 completing the sheet metal angle 54. The slits *g* and *k* permit the angle 54 to be bent as shown in Fig. 2 which forms a component of a polygonal mold to be used in a concrete floor as described in said patent.

35 The point of bending the flange on the angle 54 may be altered by substituting a pair of thicker or thinner shims for shims 9^a and 7^a.

40 In the drawings I have shown the guide collars and feed rollers set for the maximum length of strip 53. When shorter strips are desired, the guide collars 56 are set to the proper distance to accommodate the desired width sheet and the feed rollers are set at the proper relative points on their respective 45 shafts. The flanged guide rollers 50 and 51 are also set accordingly.

I claim:

50 1. In a machine of the class described, the combination of a frame having two guideways; a fixed die, having a longitudinal rib, mounted on said frame above said guideways; a movable die, having a longitudinal groove adapted to receive said longitudinal rib, mounted in said guideways; a main shaft journaled in said frame; a drive wheel mounted on said main shaft; an upper feed roller shaft journaled in said frame; a ratchet wheel mounted on said upper feed roller shaft; a lever, carrying a pawl adapted to engage said ratchet wheel, mounted on said upper feed roller shaft; a crank mounted on said main shaft; a link bar connecting said lever and said crank; a lower feed roller shaft journaled in said frame directly below said upper feed roller shaft; two slitting and perforating feed rollers mounted on said upper feed roller shaft, each roller comprising a cylinder having rectangular radial grooves in one end and semicircular radial grooves in the other end, a collar, having similar rectangular radial grooves, disposed with its rectangular radial grooves adjacent to the rectangular radial grooves of said cylinder, a collar, having similar semicircular radial grooves, disposed with its semicircular radial grooves adjacent to the semicircular radial grooves of said cylinder,

frame directly below said upper feed roller shaft; two slitting and perforating rollers mounted on said upper feed roller shaft, each roller comprising a cylinder having rectangular radial grooves in one end and similar semicircular radial grooves in the other end, a collar having similar rectangular radial grooves, disposed with its rectangular grooves adjacent to the rectangular grooves of said cylinder, a collar, having similar semicircular radial grooves, disposed with its semicircular radial grooves adjacent to the semicircular radial grooves of said cylinder; knives, having two slitting segments, disposed in said rectangular grooves and pins disposed in said semicircular grooves and firmly clamped therein; two feed rollers mounted on said lower feed roller shaft and having peripheral grooves adapted to receive the knives and pins of said slitting and perforating rollers; two perforating rollers mounted on said upper feed roller shaft, each of said perforating rollers comprising two collars, each having semicircular radial grooves, disposed with the grooves of one collar adjacent to the grooves of the other, and pins disposed in said grooves and firmly clamped therein; and two feed rollers mounted on said lower feed roller shaft adjacent to said perforating feed rollers and each having a peripheral groove adapted to receive the points of said pins.

2. In a machine of the class described, the combination of a frame having two guideways; a fixed die, having a longitudinal rib, mounted on said frame above said guideways; a shear blade mounted on the back of said fixed die; a movable die, having a longitudinal groove adapted to receive said longitudinal rib, mounted in said guideways; a shear blade bolted to the back of said movable die; a main shaft journaled in said frame; an upper feed roller shaft journaled in said frame; a ratchet wheel mounted on said upper feed roller shaft; a lever, carrying a pawl adapted to engage said ratchet wheel, mounted on said upper feed roller shaft; a crank mounted on said main shaft; a link bar connecting said lever and said crank; a lower feed roller shaft journaled in said frame directly below said upper feed roller shaft; two slitting and perforating feed rollers mounted on said upper feed roller shaft, each roller comprising a cylinder having rectangular radial grooves in one end and semicircular radial grooves in the other end, a collar, having similar rectangular radial grooves, disposed with its rectangular radial grooves adjacent to the rectangular radial grooves of said cylinder, a collar, having similar semicircular radial grooves, disposed with its semicircular radial grooves adjacent to the semicircular radial grooves of said cylinder,

- knives, having two slitting segments, disposed in said rectangular grooves, and pins disposed in said semicircular grooves and clamped therein; two feed rollers mounted 5 on said lower feed roller shaft and having peripheral grooves adapted to receive the knives and pins of said slitting and perforating feed rollers; two perforating feed rollers mounted on said upper feed roller shaft, each of said perforating feed rollers comprising two collars, each having semi-circular radial grooves, disposed with the grooves of one collar adjacent to the grooves of the other, and pins disposed in said semi-circular radial grooves and clamped therein; and two feed rollers mounted on said lower feed roller shaft directly under said perforating feed rollers and having peripheral grooves adapted to receive the points 10 of the pins in said perforating feed rollers. 70
3. In a machine of the class described, the combination of a frame having two guideways; a fixed die, having a longitudinal rib, mounted in said guideways; a shear blade bolted on the back of said fixed die; a bending plate bolted on the front of said fixed die; a shim disposed between said die and said bending plate; a movable die, having a longitudinal groove adapted to receive 15 said longitudinal rib, mounted in said guideways; a shear blade bolted on the back of said movable die; a plate bolted on the front of said movable die; a shim disposed between said movable die and said plate; a main shaft journaled in said frame; an upper feed roller shaft journaled in said frame; a ratchet wheel mounted on said upper feed roller shaft; a lever, carrying a pawl adapted to engage said ratchet wheel, mounted on said upper feed roller shaft; a crank mounted on said main shaft; a link bar connecting said lever and said crank; a lower feed roller shaft journaled in said frame directly below said upper feed roller 20 shaft; two slitting and perforating feed rollers mounted on said upper feed roller shaft, each roller comprising a cylinder having rectangular radial grooves in one end and semicircular radial grooves in the other end, a collar having similar rectangular radial grooves and disposed with its rectangular radial grooves adjacent to the rectangular radial grooves of said cylinder, a collar having similar semicircular radial 25 grooves and disposed with its semicircular radial grooves adjacent to the semicircular radial grooves of said cylinder, knives, having two slitting segments, disposed in said rectangular radial grooves and pins disposed in said semicircular radial grooves; two feed rollers mounted on said lower feed roller shaft and having peripheral grooves adapted to receive the knives and pins of said slitting and perforating feed rollers; two perforating feed rollers mounted on 30 75
- said upper feed roller shaft, each of said perforating feed rollers comprising two collars having semicircular radial grooves and disposed with the grooves of one collar adjacent to the grooves of the other, and pins disposed in said grooves; and two feed rollers mounted on said lower feed roller shaft and having peripheral grooves adapted to receive the points of said pins in said perforating feed rollers. 80
4. In a machine of the class described, the combination of a frame having two guideways; a fixed die, having a longitudinal rib, mounted on said frame above said guideways; a shear blade bolted on the back of said fixed die; a movable die, having a longitudinal groove adapted to receive said longitudinal rib, mounted in said guideways; a shear blade bolted on the back of said movable die; a main shaft journaled in said frame; brackets mounted on said movable die; a supplementary shaft journaled in said brackets; off-bearing arms mounted on said supplementary shaft; a tilting arm mounted on said supplementary shaft; a slotted bar, having its slotted portion disposed around said main shaft and its upper end connected to said tilting arm; and a segmental cam mounted on said main shaft and adapted to operate said slotted bar. 85 90 95
5. In a machine of the class described, the combination of a frame having two guideways; a fixed die, having a longitudinal rib, mounted on said frame above said guideways; a movable die, having a longitudinal groove adapted to receive said longitudinal rib, and transverse grooves in its upper surface; a main shaft journaled in said frame; an upper feed roller shaft journaled in said frame; a ratchet wheel mounted on said upper feed roller shaft; a lever, carrying a pawl, mounted on said upper feed roller shaft; a crank mounted on said main shaft; a link-bar connecting said lever and said crank; brackets mounted on said movable die; a supplementary shaft mounted in said brackets; off-bearing arms mounted on said supplementary shaft and normally resting in the transverse grooves in said movable die; a tilting arm mounted on said supplementary shaft; a slotted bar having its slotted portion disposed around said main shaft and its upper end connected to said tilting arm; a roller mounted on said slotted bar; and a segmental cam mounted on said main shaft and adapted to cooperate with said roller. 100 105 110 115 120
6. In a machine of the class described, the combination of a frame having two guideways; a fixed die, having a longitudinal rib, mounted on said frame above said guideways; a movable die mounted in said guideways and having a longitudinal groove adapted to receive said longitudinal rib, and transverse grooves in its upper surface, a 125 130

main shaft journaled in said frame; brackets mounted on said movable die; a supplementary shaft journaled in said brackets; off-bearing arms mounted on said supplementary shaft and normally resting in the transverse grooves in said movable die; a tilting arm mounted on said supplementary shaft; a slotted bar having its slotted portion disposed around said main shaft and its upper end connected to said tilting arm; a roller mounted on said slotted bar; a segmental cam mounted on said main shaft and adapted to cooperate with said roller; a pair of shafts having sprockets thereon, journaled in said frame; sprocket chains, having standards thereon, mounted on said sprockets; and a crank mounted on one of said shafts.

7. In a machine of the class described, the combination of a frame having two guideways; a fixed die, having a longitudinal rib, mounted on said frame above said guideways; a shear blade bolted on the back of said fixed die; a bending plate bolted on the front of said fixed die; a movable die, having a longitudinal groove adapted to receive said longitudinal rib, transverse grooves in its upper surface, and downwardly extending slides, mounted in said guideways; rollers mounted on said slides; a shear blade bolted on the back of said movable die; a main shaft journaled in said frame; and cams mounted on said main shaft and adapted to cooperate with said rollers.

8. In a machine of the class described, the combination of a frame having two guideways; a fixed die, having a longitudinal rib, mounted on said frame above said guideways; a shear blade bolted on the back of said fixed die; a bending plate bolted on the front of said fixed die; a movable die, having a longitudinal groove adapted to receive said longitudinal rib, mounted in said guideways; rollers mounted on said fixed die; a shear blade bolted on the back of said movable die; a plate bolted on the front of said movable die; a main shaft journaled in said frame; cams mounted on said main shaft and adapted to cooperate with said rollers; an upper feed roller shaft journaled in said frame; a ratchet wheel mounted on said upper feed roller shaft; a lever, carrying a pawl adapted to engage said ratchet wheel, mounted on said upper feed roller shaft; a crank mounted on said main shaft; a link-bar connecting said lever and said crank.

9. In a machine of the class described, the combination of a frame having two guideways; a fixed die, having a longitudinal rib, mounted on said frame above said guideways; a shear blade bolted on the back of said fixed die; a bending plate bolted on the front of said fixed die; a movable die, having a longitudinal groove adapted to receive

said longitudinal rib, transverse grooves in its upper surface, and downwardly extending slides, mounted in said guideways; rollers mounted on said slides; a shear blade bolted on the back of said movable die; a main shaft journaled in said frame; cams mounted on said main shaft and adapted to cooperate with said rollers; brackets mounted on said movable die; a supplementary shaft journaled in said brackets; off-bearing arms mounted on said supplementary shaft and normally resting in the transverse grooves in said movable die; a tilting arm mounted on said supplementary shaft; a slotted bar having its slotted portion disposed around said main shaft and its upper end connected to said tilting arm; a roller mounted on said slotted bar; and a segmental cam mounted on said main shaft and adapted to cooperate with said roller.

10. In a machine of the class described, the combination of a frame having two guideways; a fixed die, having a longitudinal rib, mounted on said frame above said guideways; a shear blade bolted on the back of said fixed die; a movable die, having a longitudinal groove adapted to receive said longitudinal rib, and downwardly extending slides, mounted in said guideways; rollers mounted on said slides; a shear blade bolted on the back of said movable die; a main shaft journaled in said frame; cams mounted on said main shaft and adapted to cooperate with said rollers; an upper feed roller shaft journaled in said frame; a lower feed roller shaft journaled in said frame directly below said upper feed roller shaft; a gear mounted on said upper feed roller shaft and a gear mounted on said lower feed roller shaft and meshed with each other; a ratchet wheel mounted on said upper feed roller shaft; a lever, carrying a pawl adapted to engage said ratchet wheel, mounted on said upper feed roller shaft; a crank mounted on said main shaft; a link-bar connecting said lever and said crank; and feed rollers mounted on said feed roller shafts.

11. In a machine of the class described, the combination of a frame having two guideways; a fixed die, having a longitudinal rib, mounted on said frame above said guideways; a shear blade bolted on the back of said fixed die; a movable die, having a longitudinal groove adapted to receive said longitudinal rib, and downwardly extending slides, mounted in said guideways; rollers mounted on said slides; a shear blade bolted on the back of said movable die; a main shaft journaled in said frame; cams mounted on said main shaft and adapted to cooperate with said rollers; an upper feed roller shaft journaled in said frame; a ratchet wheel mounted on said upper feed roller shaft; a lever, carrying a pawl adapted to engage said ratchet wheel, mounted on

said upper feed roller shaft; a crank mounted on said main shaft; a link-bar connecting said lever and said crank; a lower feed roller shaft journaled in said frame directly below said upper feed roller shaft; two slitting and perforating feed rollers mounted on said upper feed roller shaft, each roller comprising a cylinder having rectangular radial grooves in one end and semicircular radial grooves in the other end, a collar having similar rectangular radial grooves and disposed with its rectangular radial grooves adjacent to the rectangular radial grooves of said cylinder, a collar having similar semicircular radial grooves and disposed with its semicircular radial grooves adjacent to the semicircular radial grooves of said cylinder, knives, having two slitting segments, disposed in said rectangular radial grooves, 10 and pins disposed in said semicircular radial grooves; and two feed rollers mounted on said lower feed roller shaft and having peripheral grooves adapted to receive the knives and pins of said slitting and perforating feed rollers.

12. In a machine of the class described, the combination of a frame having two guideways; a fixed die, having a longitudinal rib, mounted on said frame above said guideways; a movable die, having a longitudinal groove adapted to receive said longitudinal rib, and downwardly extending slides, mounted in said guideways; rollers on said slides; a main shaft journaled in said frame; cams mounted on said main shaft and adapted to cooperate with said rollers; an upper feed roller shaft journaled in said frame; a lower feed roller shaft journaled in said frame directly below said upper feed roller shaft; two slitting and perforating feed rollers mounted on said upper feed roller shaft, each roller comprising a cylinder having rectangular radial grooves in one end and semicircular radial grooves in the other end, a collar having similar rectangular radial grooves and disposed with its rectangular radial grooves adjacent to the rectangular radial grooves of said cylinder, a collar having similar semicircular radial grooves and disposed with its semicircular radial grooves adjacent to the semicircular radial grooves of said cylinder, knives, having two slitting segments, disposed in said rectangular radial grooves and pins disposed in said semicircular radial grooves; two feed rollers mounted on said lower feed roller shaft and having peripheral grooves adapted to receive the knives and pins of said slitting and perforating feed rollers; two perforating feed rollers mounted on said upper feed roller shaft, each comprising two collars having semicircular radial grooves and disposed with the semicircular radial grooves of one collar adjacent to the semicircular radial grooves of the other, and pins disposed in said semicircular radial grooves; two feed rollers mounted on said lower feed roller shaft and having peripheral grooves adapted to receive the points of said pins in said perforating feed rollers; two guide collars mounted on said lower feed roller shaft; and a shaft journaled in the rear of said frame, having two flanged guide rollers and a central supporting roller mounted thereon.

other, and pins disposed in said semicircular grooves.

13. In a machine of the class described, the combination of a frame having two guideways; a fixed die, having a longitudinal rib, mounted on said frame above said guideways; a shear blade bolted on the back of said fixed die; a movable die, having a longitudinal groove adapted to receive said longitudinal rib, and downwardly extending slides, mounted in said guideways; rollers mounted on said slides; a shear blade bolted on the back of said movable die; a main shaft journaled in said frame; cams mounted on said main shaft and adapted to cooperate with said rollers; an upper feed roller shaft journaled in said frame; a ratchet wheel mounted on said upper feed roller shaft; a lever, carrying a pawl, adapted to engage said ratchet wheel, mounted on said upper feed roller shaft; a crank mounted on said main shaft; a link-bar connecting said lever and said crank; a lower feed roller shaft journaled in said frame directly below said upper feed roller shaft; a gear mounted on said upper feed roller shaft and a gear mounted on said lower feed roller shaft and meshed with each other; two slitting and perforating rollers mounted on said upper feed roller shaft, each roller comprising a cylinder having rectangular radial grooves in one end and semicircular radial grooves in the other end, a collar having similar rectangular radial grooves and disposed with its rectangular radial grooves adjacent to the rectangular radial grooves of said cylinder, a collar having similar semicircular radial grooves and disposed with its semicircular radial grooves adjacent to the semicircular radial grooves of said cylinder, knives, having two slitting segments, disposed in said rectangular radial grooves and pins disposed in said semicircular radial grooves; two feed rollers mounted on said lower feed roller shaft and having peripheral grooves adapted to receive the knives and pins of said slitting and perforating feed rollers; two perforating feed rollers mounted on said upper feed roller shaft, each comprising two collars having semicircular radial grooves and disposed with the semicircular radial grooves of one collar adjacent to the semicircular radial grooves of the other, and pins disposed in said semicircular radial grooves; two feed rollers mounted on said lower feed roller shaft and having peripheral grooves adapted to receive the points of said pins in said perforating feed rollers; two guide collars mounted on said lower feed roller shaft; and a shaft journaled in the rear of said frame, having two flanged guide rollers and a central supporting roller mounted thereon.
